(Cl. D34—15)

To all whom it may concern:

Be it known that I, Joseph Reich, a citizen of the United States, residing at the Bronx, New York, in the county of Bronx and State of New York, have invented a new, original, and ornamental Design for a Rotary Pull Toy, of which the following is a specification, reference being had to the accompanying drawing, forming a part thereof.

In the drawing:

Fig. 1 is a perspective view of a rotary pull toy, showing my new design.

Fig. 2 is a side elevational view, and

Fig. 3 is a top plan view of the same.

I claim:

The ornamental design for a rotary pull toy, as shown.

JOSEPH REICH.
